GLASS-BLOWING MACHINE

Samuel A. Forter, Pittsburgh, Pa., assignor to
 Forter-Teichmann Company, Pittsburgh, Pa.,
 a corporation of Pennsylvania

Application September 4, 1942, Serial No. 457,245

3 Claims. (Cl. 49—19)

This invention relates to glass-blowing machinery. In an application for Letters Patent of the United States, Serial Number 298,775, filed October 10, 1939, by Henry F. Teichmann, now Patent No. 2,357,702, granted Sept. 5, 1944 and owned in common with the invention herein disclosed, machinery is described for blowing glass articles, typically bottles. My present invention is found in improvements that render such machinery better adapted to conditions of production. A machine of the sort referred to is capable of producing bottles (for example) with relatively great speed and in relatively large quantities; with the effect that, in the hands of particular users, its capacity to produce may exceed the need, and the machine may of necessity stand idle (with economic disadvantage) for an unduly great portion of the time. My present invention has effect in overcoming and correcting in greater or less degree that disadvantage. The invention consists, specifically, in an adaptation of the machine for the concurrent and continuous production of articles of more shapes or sizes than one. The manufacturer, accordingly, having in hand orders for so many articles of one sort and so many of another, may adapt a single machine, running for a larger portion of the time, to produce the whole, rather than find himself under the practical necessity of providing two machines and running each for a smaller portion of the time. Obviously, instead of providing two entire machines, it would be possible for the manufacturer to provide himself with two complete sets of molds alternately applicable to a single machine; but even over such an adaptation my invention affords substantial economies.

In the accompanying drawings Fig. I is a view partly in side elevation, partly in section, and in some degree diagrammatic, of glass-blowing machinery that embodies the improvements of my present invention. Fig. II is a fragmentary view, showing to larger scale and in side elevation the detail of structure in which my invention centres. Fig. III is a view in vertical and transverse section, on the plane indicated by the broken line III—III, Fig. II. Fig. IV is a view that, corresponding to Fig. III, shows certain parts in alternate operative positions. Fig. V is a view in plan from above of the portion of the apparatus shown in Figs. II and III (from the showing of Fig. V, however, a certain rail has been omitted). Fig. VI is a fragmentary and diagrammatic view, corresponding to Fig. I and illustrating a modification of structure within the field of the invention. Fig. VII is a fragmentary view to yet larger scale,

corresponding to Fig. IV, but in further illustration of the modification of Fig. VI.

The machine includes a plurality of traveling molds severally formed of mold parts 1 and 2. A succession of plates 3, with the plates articulated as shown in Fig. V, is formed into an endless chain. The axles upon which the plates are articulated project laterally and carry rollers 4. A pair of stationary guideways 5, spaced apart 10 transversely of the apparatus, and a pair of rotary sprocket wheels 6, also spaced apart, receive the rollers 4 and support the chain in the position shown in Fig. I, it being understood that the two sprocket wheels stand one behind the other in the line of sight in this figure of the drawings. The chain extends in upper and lower horizontal reaches, interconnected by rounded courses at the ends. The sprocket wheels, it may be understood, are suitably driven by a motor (not shown); and by such drive the endless chain of plates 3 is caused to advance in counterclockwise course, as seen in Fig. I, and as indicated by arrows. Each mold part 1 consists of two equal and relatively symmetrical portions, divided on an axial plane, and, in the cycle of machine operation, these mold portions close, to serve unitedly their essential mold function, and open to release the finished article. The two portions of each mold part 1 are severally mounted upon slides 8 that are 20 borne in pairs, a pair upon each plate 3. The slides are mounted to move upon plates 3 in direction transverse to the line of advance of the plates. The slides are provided with vertically extending posts upon which rollers 9 are mounted. 25 The rollers 9 engage stationary guides 10, and the guides 10 are so proportioned that, as the plates advance in their course, the portions of the successive mold parts 1, in ordered progress, close and open again. The closed mold parts 1 30 severally and successively receive (at A, Fig. I) a succession of gobs 9 of hot and plastic glass; the charged mold parts 1 are (at B) successively united with the mold parts 2, and within the so completed molds the shaping of the articles is 35 completed. The molds deliver (at C) successive finished articles.

The guides 10 are so proportioned that as the mold parts 1 advance to the position A, the two portions of which each is composed close automatically together; and as approach is made to the position C, the portions of the mold parts 1 separate, to allow the escape of the molded article.

Cooperating with the endless succession of plates 3 that carry the mold parts 1 is a second endless succession of plates 38 that carry severally

the mold parts 2. The plates 38 are articulated to form a second endless chain. The axles upon which the plates 38 are articulated are also extended and carry rollers 39. The rollers travel in stationary guideways 40. The endless chain formed of the plates 38, supported and guided by the means described, extends in upper and lower horizontal reaches, interconnected by rounded courses at the ends. The upper horizontal reach of this second endless chain is arranged immediately beneath and at an accurately spaced interval from the lower horizontal reach of the endless chain first described. The plates 38 carry rigidly, each a mold part 2. The upper reach of the lower endless chain extends in the direction of travel (to the right, Fig. I) beyond the lower reach of the upper chain.

Details of the structure and organization of the guides 10, the guideways 40, and the construction and operation of the molds may be obtained by reference to the above-noted Teichmann application.

The plates 38 carry clamps 45, by which the advancing mold parts 1, borne by the upper chain, are united one by one (at B) with the mold parts 2, borne by the lower chain. By this union the molds are completed; and by this union the lower endless chain is integrated with the upper chain, so that it moves in unison with the upper chain. The direction of the consequent movement of the lower chain is clockwise, as indicated by an arrow, Fig. I.

Means are provided by which, as the lower chain advances, the clamps 45 automatically close (at B) upon the mold parts brought together at that point; and they are automatically opened again toward the right-hand end of the upper reach of the lower chain, to allow the separation of the mold parts, as indicated in Fig. I. Such means are illustrated and described in Teichmann application Serial No. 298,775 filed October 10, 1939.

Each plate 3 of the upper chain carries a vertically reciprocable plunger 11. This plunger is normally held by spring tension in retracted position; but in the course of advance the plunger is engaged by a stationary abutment, and in consequence it is projected against spring tension into the space within the portions of mold part 1 which, at that point in their progress, have closed one upon another. The plunger 11 indeed, when so advanced, becomes itself a mold member. At the point A, Fig. I, the plunger 11 is in its advanced position of cooperation with the closed mold part 1. The abutment that effects the projection of the plunger 11 is shown in Fig. I to consist of a bar 12 having an oblique face to meet the rollers 11a with which the end of the advancing plunger 11 is equipped. The bar is continued in a sector-shaped block or cam 13. And it will be seen that the surface against which the plunger rests, and by resting is held in projected position, is parallel with the course of the advancing plate 3 as the plate 3 comes to position A and advances thence upon the descending rounded course of the endless chain.

As disclosed in the above-noted Teichmann application, the plate 3 is interiorly chambered, and from the chamber there is an opening through a cylindrical boss 15 that rises from the face of the plate. The two portions of the mold part 1 close upon the boss 15. The parts are nicely machined, so that the closure is substantially air-tight. Means are provided for establishing within the chamber, in the course of progress of the plate, alternate conditions of suction and compression.

The condition of suction is established as the plate 3 comes to position A, and is maintained as the plate advances from the position A and during a portion of the downward and descending rounded course. At an intermediate point in that descent the condition of suction is relieved; and at substantially the same point the plunger 11 is released and under spring tension recedes from advanced position in the mouth of the closed mold part 1. Immediately thereafter a condition of compression is established within the chambered plate 3. The means for establishing the condition of suction are not of immediate concern, and need not now be enlarged upon; it is with the means for establishing the condition of pressure that the present invention has immediately to do.

As disclosed in said Teichmann application, a chamber 18 within the plate 3 may be understood to be constantly maintained filled with air under adequate glass-blowing pressure. From chamber 18 a passageway 180 leads to that other chamber within plate 3 already alluded to, from which there is constant and open communication, through the orificed boss 15—the boss upon which the two portions of the mold part 1 close in substantially air-tight union. Communication from chamber 18 through the passageway 180 is, at proper time in the course of the advance of plate 3, effected by the unseating of a spring-backed valve 21.

The stem of valve 21 extends through plate 3 and is at its outer end equipped with a roller 27a; on one side of the machine a sector-shaped plate 30 and a rail 31 are provided; and, as the succeeding plates 3 advance, the engagement of the roller-equipped valve stems with these relatively stationary members 30 and 31 effects the unseating of the valves 21 of the succeeding plates. The valves continue in unseated position so long as such engagement continues, and during such interval air enters and fills the now closed mold 1, 2 and maintains within the mold glass-blowing pressure. When the roller-equipped valve stem passes (from left to right, Fig. I) beyond the end 45 of rail 31, valve 21 closes under spring tension, and blowing pressure is cut off.

The apparatus is arranged in suitable assembly with a glass tank or fore-hearth 48, and a delivery orifice with a flow-controlling rod 49, adjustable in its position above the orifice, is arranged to deliver freely and continuously under gravity a stream G of molten glass, in line directly above the series of mold parts 1.

A pair of shear blades 50 is mounted to reciprocate across the stream G of glass, and, in their cooperation, to shear the descending column of glass into a succession of gobs g, one of which is diagrammatically shown in Fig. I within a closed mold part 1. The shear blades are advantageously double-edged and are so organized that with each traverse they cooperate in severing a gob from the stream G.

Operation may be followed, with reference to Fig. I. It will be understood that the endless chain of plates 3, carrying the mold parts 1, is being driven in counter-clockwise course, and that the shear blades 50, 50 are reciprocating, cutting into discrete gobs g the continuously descending column G of glass.

The mold parts 1, as these advance from right to left along the upper reach of travel, are in inverted position, and are open above. As they advance, their two portions, separated at C, are brought together, and, being brought together, they come to position A, ready to receive the glass.

As each mold part 1 in turn comes to position A, it receives a severed gob g of glass falling from the shears.

At the moment when the mold part 1 so receives its gob, the plunger 11 has, by the engagement of its stem with rail 12, been projected upward, into the mouth of the mold part. And at the same time, it may be understood, a condition of suction is set up in the mouth of the mold part and beneath the fallen gob. Under excess of pressure from above the molten glass then is molded in the lower end of the mold part 1 and around the tip of the upwardly extended plunger 11. Thus the mouth of the article (in the example given, a bottle) is shaped. Such shaping is effected while the mold part, borne by the advancing plate, advances through the earlier portion of its descending and rounded course. The shaped portion of the body of glass is by contact with the mold parts solidified, while elsewhere the body remains plastic.

At a predetermined point in this descending course the condition of suction is relieved and the plunger 11 is withdrawn. Immediately thereafter, by the unseating of valve 27, air under pressure is admitted to and fills the cavity in the partially shaped gob of glass that has been left vacant by the retraction of plunger 11. The blowing of the still plastic portion of the glass body then begins.

Operation is so timed that, before the swelling bulb of glass reaches the open end of mold part 1, the mold part 1, now inverted to erect position, has come to registered engagement with and clamped to its companion mold part 2 that is borne by the lower endless chain.

Throughout the extent of rail 31 the valve 27 continues in open position, and during this interval of time compressed air blows the bottle to completion within the now complete mold.

When the roller-equipped stem of valve 27 passes beyond the end of rail 31, the valve, under spring tension, closes. Thereafter the clamps 45 open and the sections of the mold part 1 spread apart. This is effected before the mold reaches the right-hand end of the lower horizontal reach of travel of the upper endless chain. In the further progress the mold part 1 rises free, and the mold part 2 continues in its further horizontal course, with the completed bottle standing free upon it. At the point C the bottle may be removed.

The machine as thus far described, equipped with a set of identical molds, is adapted, manifestly, to produce identical pieces; and this, as may be inferred, at a relatively rapid rate. My present invention is found in adaptation of a machine of the character described to the production of articles of various shapes, sizes, and proportions. It is manifest that the mold cavity defined by the mold parts 1 and 2 may be proportioned as the maker will; it is manifest that by control of and change in the position of the rod 49, the size of the gobs g of glass may be varied; and it remains only to vary (and herein lies the invention) the duration of the blowing step in machine operation. As shown in Figs. I-V, the rail 31 is made of a plurality of parts—a stationary part which the roller 27a of the valve stem first engages in its advance beyond the surface of cam 30 (to this stationary part of the rail the reference numeral 31 is immediately applied) and an extension 31a that is movable and that may be brought alternately to continuity with the stationary part to be effective in continuity with part

31 upon the valve stem, or may be carried aside to ineffective position.

Accordingly, the part 31a is mounted upon the work arms of two identical bell-crank levers 50 (Fig. II) that are pivoted upon a common axis in a stationary portion of the machine (conveniently upon the adjacent rail 5), and a bar 53 extends between and unites the power-arms of the levers (Figs. II and IV). The two levers, the rail part 31a, and the bar 53 together constitute a rigid structure, pivotally movable upon the axis of the levers. Springs 51 tend to turn this structure in a clock-wise direction and to hold the extensions 31a of the rails in retracted and inactive position, as shown in Fig. IV.

As between successive molds, let it be understood that the mold in the lead is intended to have formed within it a bottle or other receptacle, which because of its size and proportions requires the application of blowing pressure for a relatively short time interval, while the next succeeding mold is intended to have formed within it a bottle or other receptacle, which requires blowing pressure for a relatively long time. Let it be understood further that the main portion 31 of the rail suffices to afford blowing pressure sufficient for the first of the two articles, while the prolongation of the rail in the extension 31a is required for the blowing of the second article. The plate 3 that carries the second mold is equipped, as the plate 3 that carries the first is not, with an upstanding flange 52, elongate in the direction of mold advance. This flange, in the advance of the plate 3, engaging bar 53, swings the bell-crank lever structure and brings the rail part 31a from the position shown in Fig. IV to that shown in Figs. II and III. When the rail extension 31a is in the last-named position, blowing pressure continues to be effective within the mold-contained article through a correspondingly prolonged interval of time. As successive plates 3 are equipped with or lack the flange 52, the duration of blowing pressure within the article under fabrication will be long or short. The flange 52 is deflected at its advance end to make proper engagement with the bar 53 in its advanced position and to effect the gradual swinging of the spring-backed lever structure.

Manifestly a second rail extension, such as 31a, similarly arranged and controlled, might be provided, to adapt the machine to produce automatically yet another variety of blown article.

An alternate arrangement of means to accomplish the same end, of selective duration of the period of continuance of blowing pressure, is illustrated in Figs. VI and VII. In this case the rail upon which the roller-equipped stem of valve 27 makes bearing is integral, but is set in oblique position; so that, as the mold-bearing plate 3 advances in left-to-right course, Fig. VI, the valve 27 gradually closes under spring tension. In this case, however, the stem of the valve 27 is made telescopically extensible in length, and a set-screw 27b is provided by which the stem parts may be secured at any desired effective length of stem. By proper adjustment of the stems of the valves 27 in succeeding plates, the duration of the time of application of blowing pressure within the succeeding articles may be predetermined.

As in the machine of the Teichmann application named above, the point at which blowing pressure first gains admittance to the blank within the mold is nicely determined by the minute adjustment of the sector-shaped plate or cam disk 30 upon its centre of turning.

By such means a single machine may be set for the continued production of articles of two or more sorts, differing in size or shape or both, and in predetermined relative quantities.

I claim as my invention:

1. In a machine for blowing articles of plastic material including a chain of articulated members mounted for travel in cyclic course and carrying molds, each adapted to receive a plastic blank, and passages in the chain members for connecting the molds severally to a source of compressed air, the invention herein described which comprises means for severally opening and closing said passages to air flow, and means including a rail extending longitudinally of said course of chain travel for operating said passage opening and closing means, said rail being of adjustable effective length as between successive molds whereby the interval, during which the air passage to one of said molds is open, is greater than the interval during which the air passage to another mold is open.

2. The structure of claim 1, said passage opening and closing means comprising valves having

stems arranged in mold travel to engage said rail, said rail having a section mounted for movement to and from position to be engaged by said valve stems, and means arranged in the course of mold travel to shift said rail section from inactive to valve-stem-engaging position.

3. In a machine for blowing articles of plastic material including a plurality of molds mounted for travel in predetermined course and each adapted to receive a plastic blank, passages for connecting the molds severally to a source of compressed air, and valves severally controlling said passages, the invention herein described comprising stems for said valves severally adjustable in effective length, and a rail set in oblique position with respect to the direction of mold advance and adapted to be successively engaged by said valve stems as the molds travel in said course, whereby the intervals of mold advance, during which the valves continue in open position, may be varied and rendered unequal as between the succeeding molds.

SAMUEL A. FORTER.
